CLAIM

The ornamental design for a mobile communication terminal with graphical user interface, as shown and described.

DESCRIPTION

FIG. 1 is a front view of a mobile communication device with graphical user interface showing our new design; and, FIG. 2 shows the design of FIG. 1 in environment.

The broken lines shown in the drawings of a mobile communication terminal and certain graphic features of the graphical user interface form no part of the claimed design.

1 Claim, 2 Drawing Sheets
